EX

OR D 12,612

No. 12,612

Dec. 20, 1881

Cut 256.

UNITED STATES PATENT OFFICE.

H. CLAY BASCOM, OF TROY, AND TOBIAS S. HEISTER, OF LANSINGBURG,
ASSIGNORS TO N. S. VEDDER PATTERN WORKS, BASCOM, GALBRAITH
& CO., OF TROY, NEW YORK.

DESIGN FOR A STOVE.

SPECIFICATION forming part of Design No. 12,612, dated December 20, 1881.

Application filed November 19, 1881. Term of patent 7 years.

To all whom it may concern:

Be it known that we, H. CLAY BASCOM, a citizen of the United States, residing in the city of Troy, in the county of Rensselaer and State of New York, and TOBIAS S. HEISTER, a citizen of the United States, residing in the village of Lansingburg, in said county and State, have jointly invented and produced a new and original Design for a Cooking-Stove, 5 of which the following is a specification, reference being had to the accompanying cut, print, or engraving of a stove having said new design.

The design for the panel ornament A consists of a raised flat-faced block - form part 15 having twenty equal, or nearly equal, straight side edges, forming two pairs of diametrically-opposite sharply - projecting angles, *a*, four pairs of projecting obtuse angles, *b*, and four 20 pairs of obtuse re-entering angles, *c*, in combination with the compound incised face ornament *d*, divided by straight lines into differently-ornamented pairs of quarters, all shaped and arranged substantially as shown 25 in the accompanying print.

The design for the outer portion of the panel B consists of the convexly-curved edge portion *e*, arched incised ornament *f* on the narrow upper portion, the incut ornaments *g*, *g'*, 30 and *h* on the broader lower portion, and the elongated incised ornament *i* on the forwardly-extended part of the panel, and all shaped and arranged substantially as shown in the accompanying engraving.

The design for the oven-door C consists of 35 the panel ornament A, composed as described, in combination with panel B, having the ornamental parts *e f g g' h i*, and the outer molding, *j*, all shaped and arranged together sub-

stantially as shown in the aforesaid cut.

The design for the doors or raised panels D

E consists of the outer ornamental molding, *k*, in combination with the raised inner panel, *l*, having the central ornament, *m*, side ornaments, *n*, and top and bottom ornaments, *o*, 45 all shaped and arranged together substantially as shown in the aforesaid print.

The design for the legs consists of the top bent band, *p*, having the series of ornaments *q*, the central ornamented panel, *r*, the inclined 50 side panels, *s*, having ornamental fillet edges and ornaments *t*, and the ornament *u* on the contracted lower part, *v*, all shaped and combined substantially as shown in the aforesaid cut.

What we claim as our joint invention is—

1. The design for the panel A, consisting of the parts *a b c d*, all formed, shaped, and combined as set forth.

2. The design for the outer portion of the 60 panel B, consisting of the parts *e f g g' h i*, all shaped and arranged as set forth.

3. The design for the oven-door C, consisting of the ornament A, composed as specified, in combination with the panel B, having the 65 ornamental parts described, and the outer molding, *j*, as set forth.

4. The design for the doors or raised panels D E, composed of parts *k l m n o*, all shaped and arranged as set forth.

5. The design for the legs, consisting of the parts *p q r s t u v*, all shaped and combined as described.

In testimony whereof we hereunto set our hands, in the presence of two subscribing witnesses, this 17th day of November, 1881.

H. CLAY BASCOM.
TOBIAS S. HEISTER.

Witnesses:

AUSTIN F. PARK,
JAMES T. GOODFELLOW.
